E. S. CHARLES.
DELIVERY MEMBER HOIST FOR ENsilAGE CUTTERS.
APPLICATION FILED JAN. 12, 1916.
1,314,570. Patented Sept. 2, 1919.

Inventor.
Edward S. Charles.
By *Edward S. Charles*

UNITED STATES PATENT OFFICE.

EDWARD SANFORD CHARLES, OF CHICAGO, ILLINOIS, ASSIGNOR, BY MESNE ASSIGNMENTS, TO INTERNATIONAL HARVESTER COMPANY, A CORPORATION OF NEW JERSEY.

DELIVERY-MEMBER HOIST FOR ENSILAGE-CUTTERS.

1,314,570.

Specification of Letters Patent.

Patented Sept. 2, 1919.

Application filed January 12, 1916. Serial No. 71,644.

To all whom it may concern:

Be it known that I, EDWARD S. CHARLES, a citizen of the United States, residing at Chicago, in the county of Cook and State of Illinois, have invented certain new and useful Improvements in Delivery-Member Hoists for Ensilage-Cutters, of which the following is a full, clear, and exact specification.

- 10 My invention relates to delivery member hoists for ensilage cutters. It has for its object to enable an ensilage delivery member or distributor to be readily placed in position upon the delivery pipes 15 of an ensilage cutter even when the same are used in filling the tallest silos. A more specific object of my invention is to provide improved means for hoisting a delivery member, and especially one of distributor 20 form, and attaching the same to the delivery pipes at the top of the silo without it being necessary for an operator to ascend the silo and manually connect the parts. I attain these objects by providing an improved construction of hoist and connecting means whereby the delivery member may be hoisted into position upon the delivery 25 end of the delivery pipes and dropped into an operative connection therewith, the operator being upon the ground.

In the accompanying drawings I have, for purposes of illustration, shown one embodiment which my invention may assume in practice.

- 30 In these drawings:

Figure 1 is a partial side elevation of the delivery pipes extending over into a silo with the distributor hoisting means attached thereto;

- 40 Fig. 2 is a detail side elevation of the distributor hoisting means;

Fig. 3 is an end view of the construction shown in Fig. 2.

As in the usual construction, delivery pipes 45 1 are connected end to end and disposed vertically at the side of a silo, a portion of which is indicated in dotted lines at 2, the usual curved upper delivery member 3 of the pipes passing over the upper end of the 50 silo or through a suitable opening therein.

In my improved construction a suitable upstanding bifurcated bracket 4 is mounted upon this delivery member 3, and upon this bracket are fastened two supporting straps

5, one on each side, between which is journaled a sheave 6, the support 5 being braced on the frame and the rope on the sheave being held therein by a suitable upwardly and laterally disposed U-member 7. Formed preferably upon one of the feet of the bracket 60 4 is a hook member 8, open at the top and having a laterally disposed end 9 which is adapted to be received in an opening 10 formed in the upper end of a delivery member to be placed in position, shown herein 65 in the form of a distributor 11, when said member is hoisted above the end 9 by means of a rope 12 connected to the upper end of the distributor at 13 and extending upward through a slot in the hook end 9 and 70 around the sheave 6.

When my improved construction is used and it is desired to place the distributor 11 in position within the silo, the rope 12 is passed around the sheave 6 before the delivery 75 member 3 is elevated into position, and, after the latter is in position, the distributor is then hoisted until it passes beyond the end portion 9 on the hook member 8. When in this position, by suitable manipulation 80 of the rope 12, the opening 10 in the upper end of the distributor may, obviously, be brought over the hooked end of the extension 9 on the member 8, as shown in Fig. 1, so that this extension will pass through the 85 opening 10 when the distributor is again lowered and the latter will settle down into the hook portion of the member 8, as shown in Fig. 2. When in this position the rope 90 obviously may be left connected to the distributor as desired, the same extending down along the outer wall of the silo, as illustrated, in such a position that it is out of the operator's way.

Obviously, with the distributor connected 95 as shown in Fig. 2, the operator may adjust the distributor while distributing the ensilage within the silo by movement of the distributor 11 and its connected delivery sections 15 in a well-known manner, sufficient play being provided between the connections to permit free movement of the distributor. It is also obvious that when the silo is filled and an operator on the ground desires to lower the distributor, he may readily do so, and that whenever for any reason it is wished to remove the distributor before the silo is filled, this may readily be done by

simple manipulation of the rope 12 to disengage the distributor from its hook. It is also to be noted that the construction may be very readily and cheaply manufactured and applied to any standard delivery member or distributor at small expense.

While I have in this application specifically described one embodiment which my invention may assume in practice, it is, of course, to be understood that the invention may be modified and embodied in other forms without departing from its spirit, it being my object to include all such modifications within the scope of the appended claims.

What I claim as new is:

1. In combination, an ensilage deflecting member, a coöperating distributor, means for hoisting said distributor to a position adjacent said deflecting member, a portion of said distributor being positioned above said deflecting member, and means for guiding the distributor into operative position as said distributor is lowered.

2. In combination, a stationary ensilage delivery chute, a coöperating distributor, a hook carried on said chute receivable by said distributor, and hoisting means connected to said chute and distributor for hoisting said distributor to a position in which a portion of said distributor is disposed above said chute and connecting the same to the hook on said chute.

3. In a hoisting mechanism for ensilage delivery members, a delivery member, an upstanding bracket carried thereon at a point above the delivery end thereof, a hook member extending laterally over the end of

said delivery member, and a sheave journaled on said bracket above said hook member.

4. In combination, an ensilage delivery chute, a distributor, means for hoisting said distributor to operative position adjacent said chute and upwardly inclined means carried by said chute and above which the upper ends of said distributor may be hoisted for operatively connecting said chute and said distributor when the distributor is lowered into operative position.

5. In combination, an ensilage delivery chute, a distributing member, means for hoisting said distributing member to operative position adjacent said chute, and upwardly projecting means carried by said chute above which the upper ends of said distributor may be hoisted for moving said distributor over the outlet end of said chute and operatively connecting said distributor and said chute when the distributor is lowered into operative position adjacent thereto.

6. In combination, a chute having an open delivery end, a distributing member having an inlet opening, means for hoisting said distributing member to a position adjacent the delivery end of said chute, and means carried by the chute and separate from said hoisting means for engaging and guiding said distributor to a position in which the delivery end of said chute extends into and is received by the inlet opening of said distributor.

In testimony whereof I affix my signature.

EDWARD SANFORD CHARLES.
